DRILLING MACHINE

Herman Goldberg, Chicago, Ill.

Application June 26, 1942, Serial No. 448,554

7 Claims. (Cl. 77—32)

1

This invention relates to improvements in drilling machines and other machine tools in which a rotatable tool, such as a drill or a tap, has relative axial movement with respect to the work during the operation of drilling, tapping or the like. The present invention is an improvement upon that described and claimed in my copending application, Serial No. 323,648, filed March 13, 1940.

The principal object of the present invention is to provide an improved machine of the type referred to in which the axial movements of the rotating tool with respect to the work are effected, preferably, by compressed air or the like and controlled by the movement of the work to the position where it is to be engaged by the tool. Thus, in one embodiment of the invention, the tool is rotated by an electric motor and is moved axially with respect to the work by compressed air which is controlled by the movement of the work piece, to the position where it is to be engaged by the tool, to initiate the axial movement of the tool, means being provided for cushioning and automatically arresting the tool at the end of its working stroke and for promptly and automatically reversing the direction of its axial movement. This control of the initiation of the work cycle by the movement of the work piece is termed "piece part control" and it may supplement or be replaced by a manual operation, herein termed "foot pedal control." It is also possible to adjust the apparatus so that after its operation has been initiated by either one of the methods just referred to, it will perform a continuing series of work cycles without interruption.

In this improved machine, the movement of the tool to and through the work is effected by a resilient yielding pressure which is capable of permitting the movement of the tool to be entirely arrested in the event that unusual resistance is encountered during the drilling, tapping or other work operation, thereby substantially eliminating danger of breakage of the tool. The tool is returned after each forward stroke by a constantly applied air pressure which is overcome, during the forward or working stroke, by the greater air pressure which is then applied and which is exhausted to the atmosphere during the return stroke. The machine may also include means operated by compressed air or the like for gripping and holding the work piece during the working stroke of the tool, and for ejecting it when the work has been completed and the tool withdrawn.

In the preferred form of the invention, the regoing operations are controlled by an electric

2

circuit which is associated with the air pressure system by which the tool is actuated in such a manner that manual control, piece part control, or continuous automatic operation, of the apparatus may readily be brought into use at the will of the operator. This electric circuit may include a starting switch which is normally closed in one position by a part of the machine when the tool is fully retracted and which is then connected in a branch circuit adapted to be closed either by the temporary actuation of a foot pedal control switch or of a piece part control switch to energize a solenoid for opening a valve in the compressed air system and thereby initiating the forward stroke of the tool. After a predetermined limited movement of the tool, the starting switch moves automatically to another position, thereby shunting the foot pedal control and piece part control switches and continuing the circuit of the solenoid through an operating switch which maintains one closed position until the tool reaches the end of its forward stroke whereupon the operating switch is moved automatically to another position, thus deenergizing the solenoid and closing the circuit of an exhaust solenoid which then opens an exhaust valve and permits the air which produced the forward stroke to exhaust to the atmosphere while allowing the continuously applied back air pressure to produce a return stroke of the tool. At the end of the return stroke both the starting switch and the operating switch are returned to their initial positions by the movement of a part of the machine so that conditions are then in readiness for another forward stroke when the foot pedal control switch or the piece part control switch is again actuated. The circuit may preferably include a safety switch controlled by convenient means, such as the foot pedal, for permitting the operator in case of emergency to open the circuit of the operating solenoid and temporarily establish the circuit of the exhaust solenoid, thereby restoring all of the parts to their initial positions. The circuit also includes branches containing solenoids for controlling the actuation by compressed air of a work holder or fixture and comprising switches for causing these solenoids to be actuated in response to the movement of the tool so that the work piece is automatically gripped in advance of the commencement of the working stroke of the tool and is released when the work is finished. Another object is to provide an improved work holder having means for gripping the work, a switch actuated by the work piece for controlling the operating circuit of the machine and means

for ejecting the work piece when the work is completed. Other objects of the invention are to provide various improved features of construction and arrangement which will appear more fully hereinafter.

The nature of the invention will be understood from the following specification taken with the accompanying drawings in which one embodiment of the invention and modifications of certain of its parts are illustrated. In the drawings,

Figure 1 shows a front elevation of a drilling machine embodying the present invention;

Fig. 2 shows a side elevation of the machine illustrated in Fig. 1, looking toward the left as viewed in Fig. 1;

Fig. 3 shows an enlarged side elevation of a portion of the upper part of the machine illustrated in Fig. 1, with parts thereof shown in vertical section in a plane at right angles to the view of Fig. 1;

Fig. 32 shows a vertical section taken on the line 32-32 of Fig. 31;

Fig. 33 shows a vertical section taken on the line 33-33 of Fig. 31;

Fig. 34 shows a vertical section taken on the line 34-34 of Fig. 33;

Fig. 35 shows a vertical section taken on the line 35-35 of Fig. 22, illustrating the regulating valve in the operating pressure line;

Fig. 36 is a horizontal section through a casing carried by the main frame of the machine, illustrating top plan view of the solenoid valves for controlling the exhaust of compressed air from the tool operating cylinders and for controlling the admission of compressed air to and the exhaust from a work holder or fixture;

Fig. 37 shows a side elevation of the foot pedal switch and its connections to the solenoid casing, with parts of the foot pedal structure broken away and illustrated in vertical longitudinal section;

Fig. 38 shows a vertical section taken on the line 38-38 of Fig. 37;

Fig. 39 shows a vertical section through the lower portions of the solenoid valves for controlling the work holder or fixture, the section being taken on the line 39-39 of Fig. 36;

Fig. 40 shows a vertical section through the lower portion of the solenoid valve for controlling the exhaust from the tool operating cylinders, the section being taken on the line 40-40 of Fig. 36;

Fig. 41 shows a sectional view taken on the line 41-41 of Fig. 39;

Fig. 42 shows a partial top plan view of the form of work holder or fixture shown on the platen of the drilling machine illustrated in Figs. 1 and 2, with the work piece fully inserted to the position where it is to be engaged by the drill and wherein it has closed the operating circuit of the tool cylinders;

Fig. 43 shows a complete top plan view similar to that of Fig. 42, showing the work piece partially inserted and before it has actuated the switch to close the starting circuit;

Fig. 44 shows a partial front elevation of the work holder shown in Figs. 1, 42 and 43 with the tool in its elevated position;

Fig. 45 shows a vertical section taken on the line 45—45 of Fig. 43;

Fig. 46 shows a vertical section, similar to that of Fig. 45, through a modified form of work holder or fixture in which the work piece is adapted to be gripped and held by the action of compressed air or the like during the drilling operation;

Fig. 47 is an elevation of the chuck or cradle in which the work piece is mounted in the structure illustrated in Fig. 46, the view being taken in the direction of the arrows 47—47 in Fig. 46;

Fig. 48 shows a vertical section taken on the line 48—48 of Fig. 46;

Fig. 49 shows a front elevation of another form of work holder or fixture in which the work piece is held by pneumatic pressure and in which provision is also made for controlling the electric circuit of the tool operating system in response to the movement of the work piece;

Fig. 50 shows a sectional view taken on the line 50—50 of Fig. 49;

Fig. 51 is an enlarged sectional view similar to that of the upper portion of Fig. 50 but with the work piece inserted to close the circuit, and illustrating by dotted lines the position of the work piece after it has reached its final position wherein it is engaged by the tool; and

Fig. 52 is a vertical section taken on the line 52—52 of Fig. 50.

The invention is illustrated in the drawings as being embodied in a drilling machine comprising a hollow cast metal housing 55 having an enlarged base 55^a adapted to be secured upon a floor or other support. The front of the casing 55 is provided with a vertical slotted guideway 55^b on which there is mounted a vertically adjustable bracket 56 formed integrally with the work table 57 on which the piece of work 58 to be drilled is supported by a work holder or fixture 60 secured in adjusted position on the work table by cap screws 61. The bracket 56 and the table 57 are adapted to be adjusted vertically by a worm and worm wheel operated by a crank 62 and when the table 57 has reached the desired level, it is secured in adjusted position by a clamp 63. The work piece 58 is adapted to be engaged and acted upon by a drill 65 carried by a pressure platen 110 which, in turn, is actuated by compressed air or the like acting through fluid pressure mechanism carried by a cylinder block 67 which is secured to the front face of the upper part 55^c of the housing 55. The cylinder block 67 has mounted on the front thereof a valve block 66 which carries the dash-pot mechanism by which the downward stroke of the drill 65 is retarded and arrested at the end of the stroke and which has mounted therein the starting and operating switches 68 and 69, respectively, which control the circuit of the solenoid switches by which the operation of the cylinders is controlled. These switches and the major portion of the block are normally enclosed by a casing 70 which is attached to the block by screws 71.

As shown in Fig. 2, the upper end of the cylinder block is closed by a pulley casing 72 which is secured to and also encloses the upper end of the housing 55. Within the upper portion 55^c of the housing 55 there is mounted an electric motor 73 which is connected to effect the rotation of the drill 65 through the mechanism hereinafter described. The electric connections for operating this motor are brought in through the rear of the housing and the starting and stopping of the motor are controlled by push buttons 74 and 75 located in the side of the housing. The circuit

of this motor is so arranged that it may be operated at two different speeds which may be regulated by the push buttons 76 and 77, also located in the side of the housing. The electric connections thus brought into the housing may also serve to supply another electric motor 78 mounted outside of and adjacent the lower end of the housing which drives a pump 79, mounted in the base portion 55^a of the housing, by which oil or the like is elevated through a pipe 80 and discharged through a nozzle 81 onto the work piece 58 at the point where it is engaged by the tool 65. The circuit of the pump motor 78 is controlled by a switch comprising the push buttons 82 and 83 mounted in the side wall of the housing.

At one side of the base of the housing 55 there is mounted a foot pedal device 85 which includes the foot pedal switch and the safety switch and which has its connections extending through a flexible conduit 86 to the interior of the housing where connections are made with other parts of the operating circuit including the starting and operating switches 68 and 69, respectively, and the solenoid valves which control the admission 20 to and exhaust from the cylinders in the block 67 of the compressed air by which the tool 65 is moved toward and from the work. The air pressure for effecting the downward or working stroke of the tool pistons is admitted to the upper ends 25 of the cylinders in the block 67 through a pressure regulator 88 located in the housing and operated by a handle 88^a projecting through the side wall of the housing as shown in Fig. 2. The compressed air which is constantly applied for effecting 30 an upward stroke of the tool pistons when the down pressure is released flows to the lower ends of the cylinders through a pressure regulator 89, also located in the housing and having an operating handle 89^a projecting through the side 35 wall of the housing adjacent the handle 88^a. The pressure in the line in which the regulator 88 is connected is indicated by a gauge 90 and the pressure in the line in which the regulator 89 is connected is indicated by a gauge 91, these gauges 40 being located in apertures in the side wall of the housing as shown in Fig. 2. The rates of flow of compressed air through the regulators 88 and 89 are regulated by metering valves having stems 92 and 93, respectively, projecting through the 45 housing wall below the handles 88^a and 89^a, and adapted to be engaged by wrenches or the like. The connections of the compressed air lines for operating the tool and for effecting other functions are shown diagrammatically in Fig. 20 and 50 will be explained more fully hereinafter.

The foregoing description has been intended to give a general view of the principal parts of the machine before describing the details of any of these parts and reference will now be made to the 55 driving connections between the motor 73 and the drill 65 which are best illustrated in Figs. 2, 3 and 4. As there shown the motor is suspended in an aperture in the top wall of the housing with its outwardly turned flanges 73^a resting upon the flanges 55^d of the housing and provided with slots 60 engaged by studs secured in the flanges 55^d. These studs are engaged by nuts 94 which secure the motor in the desired position. By this arrangement, the motor may be shifted in the housing 65 in order to tighten the belt 95 which extends around a pulley 96 fixed on the shaft 73^b of the motor and another pulley 97 which is fixed upon a vertical hollow pulley shaft 98. The pulleys 96 and 97 are constructed in the form of truncated cones being provided with oppositely disposed

series of grooves 96^a and 97^a of different diameters, the larger grooves of each pulley being located opposite to the smaller grooves of the other pulley so that by shifting the belt 95 to different pairs of grooves the speed of the pulley shaft may be varied to cause a corresponding variation in the speed of rotation of the tool 65, in addition to the variation which may be obtained by regulating the speed of the motor through the electrical connections controlled by the push buttons 76 and 77. The shifting of the belt may be effected by moving the motor on its support and then restoring the motor to the proper position.

As shown in Fig. 4, the pulley 97 is secured by a key 99 upon the upper end of the pulley shaft 98 and it is arranged to seat upon an annular shoulder 98^a formed on an enlargement of the shaft. The upper end of the shaft is threaded for engagement by a nut 100 which is adapted to seat in a recess formed in the upper end of the pulley 97 and which holds the pulley against endwise displacement on the shaft. The upper end of the cylinder block 67 is provided with a central bore 67^a in which the pulley shaft 98 is journaled through the intermediate sealed ball bearing unit 101. The upper end of the bore 67^a is closed by a cover plate 102 secured to the upper end of the cylinder block and the lower end of the pulley shaft 98 is threaded for engagement by a pair of lock nuts 103 which hold the pulley shaft against vertical displacement in its bearing. The cylinder block is secured to the face of the housing 55^c by studs 104, shown in Fig. 5, which pass through apertures in the cylinder block and engage threaded holes in the bosses 55^e which are formed on the upper end of the housing. The cylinder block is held against lateral displacement by a vertical key 105 engaging keyways in the cylinder block and in the housing and held against vertical displacement by a screw 105^a. In this manner, the cylinder block and the pulley shaft are mounted in relatively fixed positions and the shaft is adapted to be operated continuously, when the motor 73 is in operation, for driving a vertically adjustable drill spindle 107 which has a splined engagement with the lower end of the shaft 98, as shown at 98^b in Fig. 4.

The drill spindle 107 extends downwardly through the central tubular bore of a pressure platen 110 which is adapted to be actuated for moving the drill spindle 107 longitudinally and thereby moving the drill 65 toward and from the work. The pressure platen 110 comprises an upwardly extending sleeve 110^a adapted to slide vertically in a bushing 111 mounted in the central bore 67^b of the cylinder block, and the drill spindle 107 is journaled in a ball bearing unit 112 secured in the intermediate part of the sleeve portion 110^a of the pressure platen. This ball bearing unit 112 seats against a shoulder at the end of the lower enlarged portion 107^a of the drill spindle and is held in position against that shoulder by a nut 113 engaging a threaded portion 107^b of the spindle 107. The pressure platen 110 is also provided with a downwardly extending sleeve 110^b and the lower part of the drill spindle 107 is journaled in another ball bearing unit 114 which is mounted in the lower end of the sleeve 110^b. The outer ring of this ball bearing unit seats against an annular shoulder formed on and extending inwardly from the surrounding sleeves and it is held in position against that shoulder by a nut 115 engaging the internal threads on the lower end of the sleeve, as illustrated in

Fig. 4. An annular shoulder 107^d is formed on the lower end of the spindle 107 within the nut 115 and the inner ring of the ball bearing unit is clamped against this shoulder by a pair of nuts 116 engaging the threaded portion 107^e of the drill spindle. A standard drill chuck 108 is mounted upon the tapered lower end of the drill spindle for detachably securing in place, in axial alignment with the spindle, the previously described drill 65. A nut 109 is mounted on the threaded portion 107^f of the spindle and may be rotated to force the chuck off of the spindle when desired.

The pressure platen 110 is provided with two similar oppositely extending arms 110^d which are apertured for engagement by the reduced extremities 120^a of piston rods 120, the rods being secured in fixed relation to the arms of the pressure platen by nuts 121 which are secured on the threaded ends of the piston rods. The piston rods 120 slidably engage apertures in cylinder heads 122 mounted in the lower ends of the cylinders 67^c which are formed in the cylinder blocks 67 at opposite sides of the central bore 67^b, the cylinders being equidistant from the axis of the drill spindle 107. At their upper ends, the piston rods 120 are secured to pistons 123 which have sliding fits within the cylinders 67^c. The upper ends of the cylinders 67^c are closed by detachable threaded plugs 124 and these plugs are accessible through the chambers 67^d which are formed in the upper end of the cylinder blocks and through which access may be had to the plugs 124 when the pulley casing 72 is removed. The pistons 123 are normally moved to their upper positions, as shown in Fig. 4, by the action of compressed air which is admitted to the lower ends of the pistons from a pipe 125, shown in Fig. 20, which communicates with branch pipes 125^a, shown particularly in Fig. 6, connected by threaded nipples 126 with passages 67^e extending through the cylinder blocks 67 and connecting with the lower ends of the cylinders 67^c, as illustrated in Fig. 3. The upward movement of the pressure platen 110 is limited by the engagement of the annular shoulder 110^e of the pressure platen with the lower end of the cylinder block, as shown in Fig. 4, and when the pressure platen is in this upper position the pistons 123 are spaced slightly below the plugs 124 which close the upper ends of the cylinders.

In order to move the pistons 123 downwardly against the constantly acting pressure of the compressed air admitted to the lower ends of the cylinders 67^c through the pipe 125, compressed air having a higher pressure than that in the lower ends of the cylinders is admitted at intervals to the space between the pistons 123 and the plugs 124 at the upper ends of the cylinders and this air at a higher pressure is supplied through a pipe 127, shown in Fig. 20. As shown in Figs. 7, 10 and 12, this pipe is connected through a nipple 128 with a passage 66^a extending vertically in the valve block 66. This passage communicates with an inclined passage 66^b, shown in Fig. 7, which in turn communicates with a passage 67^f formed in the face of the block 67 behind the block 68. The passage 67^f communicates with branch passages 67^g which lead to the upper ends of the cylinders 67^c so that when compressed air is admitted to the valve block 68 through the pipe 127 the pistons 123 are actuated to move the pressure platen 110 downwardly and thus carry the rotating drill 65 into engagement with the work piece 58. As the pistons 123 move downwardly, the sleeve 110^a of the

pressure platen slides in the bushing 111 and the drill spindle 107 slides downwardly within the hollow pulley shaft 98 while maintaining its splined connection therewith.

Having described the principal structural features of the drilling machine mechanism, reference will now be made to the mode of operation of the machine and to the general characteristics of the controlling system before describing the structural features of the individual parts which are embodied in the controlling system. The circuit connections of the compressed air or other fluid pressure system by which the pistons 123 are actuated and by which the tool holder may be operated, as well as the electrical connections by which the fluid pressure system is controlled, are shown diagrammatically in Fig. 20 where the branch pipes 125^a are shown as extending directly from the pipe 125 to the lower ends of the cylinders 67^c while the pipe 127 leading to the upper ends of the cylinders is shown as being connected by branch pipes directly to the upper ends of the cylinders, these branch pipes corresponding to the passages 67^c and other associated passages which are illustrated in Figs. 7 and 10. The compressed air for effecting the forward and reverse strokes of the pistons 123 is supplied through a pipe 130 which leads from an air compressor or other source of supply to a metering block 131. From this metering block 131, compressed air flows through the pressure regulator 88 and gauge 90 and then through the pipe 152 and back through the metering block and metering passages to the pipe 127 by which the compressed air is supplied to the upper ends of the cylinders 67^c. By adjusting the regulator 88, the pressure of this air may be caused to assume any desired value, as indicated by the gauge 90, and the rate of flow may be regulated by adjusting the metering screw 92 in order to cause the desired rate of flow of the air and thereby regulate the speed of the downward strokes of the pistons 123. Compressed air also flows from the passages of the metering block 131 through the pressure regulator 89 and the gauge 91 at a lower pressure to the pipe 125 which leads through branch passages to the lower ends of the cylinders 67^c, for retracting the pistons and for normally holding them in their retracted positions.

On the top of the metering block 131, there is mounted a solenoid-operated valve 133 having its stem extending into the chamber of the metering block for controlling the admission of compressed air through the passages of the block to the passages which lead to the pipe 127 by which compressed air is supplied to the upper ends of the cylinders. This solenoid-operated valve is normally closed but when it is opened, due to the energization of the solenoid, compressed air, having a higher pressure than that which is constantly applied to the lower ends of the pistons, is admitted to the upper ends of the cylinders to effect a downward stroke of the pistons 123 and the corresponding downward movement of the rotating drill 65. This action takes place against the lower pressure which exists in the lower ends of the cylinders 67^c, the pressure regulators 88 and 89 being so adjusted that the air pressure in the lower ends of the cylinders will be overcome by the higher air pressures in the upper ends of the cylinders during the downward strokes of the pistons so that the pistons are enabled to complete their full forward strokes during which there may be further compression

of the low pressure air which is trapped in the lower ends of the cylinders. During this downward stroke the compressed air in the upper ends of the cylinders moves the tool 65 with a yielding pressure and may be further compressed by the retardation of the tool if unusual resistance is encountered. It may be desirable to permit some leakage of air around the pistons 123 from the lower sides of the pistons to their upper sides and also to permit some leakage of air around the piston rods 120 where they pass through the cylinder heads 122, by omitting the use of packing, which will facilitate the operation of the machine with comparatively low air pressures on the upper sides of the pistons. At the end of the downward strokes of the pistons, the air in the upper ends of the cylinders which produced the downward strokes is permitted to exhaust through the pipe 127 and metering block 131 and through an exhaust pipe 134 which leads from the block 131 to the block 161 of an exhaust solenoid valve 135, the rate of the exhaust and the speed of the return stroke being regulated by the metering screw 93, which may be adjusted to control the flow of the exhaust air through a restricted passage. When the pistons 123 have reached the lower or forward ends of their strokes, the solenoid 135 is actuated to open a valve in the block 135^a and thus permit the air to exhaust to the atmosphere through a pipe 136 so that the back pressure continually supplied to the lower ends of the cylinders 67^c through the pipe 125 may then effect an upward or reverse stroke of the pressure platen 110 of the pistons connected thereto.

The operation of the apparatus may be initiated either by closing a switch 137 which forms a part of the foot pedal device 85 or by the closing of a switch 138 which forms a part of the work holder 60 by which the work piece is supported during the drilling operation. The first of these methods may be termed "foot pedal control" while the latter method constitutes the "piece part control" previously referred to. In order that the method of control may be selected as desired, the switches 137 and 138 are connected in a circuit which includes a controller 139 having a contact arm 139^a and three contacts, 139^b, 139^c and 139^d. When the arm 139^a is on the middle contact 139^c, the foot pedal switch 137 is included in the operative circuit and when this normally open switch is closed by pressing on the foot pedal the conductor 140 leading from the contact 139^c is connected to another conductor 141 which leads to the upper contact 68^b of the starting switch 68 previously referred to. The movable arm 68^a of this switch is normally in its upper position engaging the contact 68^b when the pistons 123 are in their upper positions, as shown in Fig. 20, so that the circuit is then continued from the switch 68 through the conductor 142 to one terminal of the solenoid-operated switch 133. The other terminal of this solenoid-operated switch 133 is connected through a conductor 143 to one of the line conductors 144 leading from a source of supply of electric current. The other supply conductor 145 has connected therein a manually operated switch 146 and, assuming this switch to be closed, the circuit is then completed from the other line conductor through a branch conductor 147 to a safety switch 148 which also forms a part of the foot pedal device 85. From this safety switch 148, a conductor 149 leads to the movable arm 69^a of the operating switch 69 which arm engages the upper contact 69^b when the pistons

11

123 are in their upper positions. This upper contact 69^b of the operating switch is connected by a conductor 150 to a conductor 151 which is connected to the movable member 139^a of the controller 139, thus completing the circuit between the two line conductors 144 and 145 through the solenoid-operated valve 133. As soon as this valve is actuated, it opens to admit compressed air supplied through the pipe 130 to the pressure regulator 88 and the gauge 90 from which it is returned by a pipe 152 to the metering block 131 through which it flows at a rate controlled by the metering screw 92 to the pipe 121 by which it is conveyed to the upper ends of the cylinders 67^c to initiate the downward strokes of the pistons 123. As soon as the downward stroke of the pistons 123 has proceeded to a limited extent, for example, one sixteenth of an inch, the movable member 68^a of the starting switch 68 drops by gravity and engages the lower switch contact 68^c, but the movable member 68^a of the operating switch 69 retains its upper position, as herein-after described, until the downward stroke is completed. Upon engagement of the movable member 68^a of the starting switch with the lower contact 68^c, a circuit is completed from the conductor 150 through the conductor 153 and the switch 68 directly to the conductor 142, thus providing a new circuit connection for maintaining the energization of the solenoid 133 and allowing the operator to release the foot pedal switch 137 which then automatically returns to its open position.

The pistons 123 then continue their downward movement while the drill 65 performs its drilling function and, when the pistons reach the lower limits of their strokes, the movable arm 69^a of the operating switch 69 is permitted to move downwardly into engagement with the lower contact 69^c of this switch. When this occurs, the conductor 149 leading from the supply line 145 is connected through the switch 69 to a conductor 154 which is connected directly to one terminal of the exhaust solenoid switch 135. The other terminal of the switch 135 is connected by a conductor 155 to the line conductor 144, thus completing the circuit of the solenoid-operated switch 135 which then opens the exhaust valve in the block 161 and allows the compressed air in the upper ends of the cylinders 67^c to exhaust to the atmosphere through the pipe 121, block 131, pipe 134, block 161 and pipe 136. This exhaust connection being established, the pistons 123 are promptly restored to their upper positions by the constantly acting air pressure which is supplied to the lower ends of the cylinders 67^c through the pipe 125 and its branch connections. As the pistons 123 reach the upper ends of their strokes, the movable members 68^a and 69^a of the starting switch and operating switch, respectively, are restored to their upper positions shown in Fig. 20, in readiness for another operation.

If, at any time during the downward strokes of the pistons 123, an accident occurs, such as the breaking of a drill or the removal of the work piece from its proper position on the holder, the operator may instantly arrest the downward stroke and restore the pistons 123 to their upper positions by pressing forwardly on the foot pedal device 85 to move the arm 148^a of the safety switch 148 out of engagement with the upper contact 148^b and into engagement with the lower contact 148^c. This disconnects the circuit from the line conductor 145 through the conductor 149 to the operating switch 69 and establishes a new circuit from the line conductor 145 through the switch

148 to a conductor 156 which leads directly to the conductor 154, thus completing the circuit of the exhaust solenoid switch 135 through the conductor 155 to the other line conductor 144 and causing the valve 133 to be opened, so that the pressure on the upper sides of the pistons 123 is exhausted to the atmosphere and these pistons are restored to their upper positions by the back pressure which is supplied from the pipe 125.

Instead of initiating the operation of the machine by the foot pedal control just described, the arm 139^a of the controller 139 may be moved into engagement with the contact 138^b, as shown by dotted lines in Fig. 20, thus cutting the foot pedal switch 137 out of the circuit and at the same time establishing a connection from the conductor 151 through a conductor 158 to the movable member 138^a of the piece part control switch 138. This switch is normally open and it is so arranged that when the work piece to be controlled is inserted in the holder 60, as hereinafter described, the work piece engages the switch and causes the movable member 138^a to engage the contact 138^b. The contact 138^b is connected through a conductor 158 to the conductor 141, previously described, thereby closing the circuit between the conductors 141 and 150 to accomplish the same result as is brought about by the closing of the foot pedal switch 137. In this way, the placing of the work piece in operative position on the work holder is utilized for closing the circuit of the starting switch 68 and initiating the downward movement of the pistons 123 and the rotating tool 65, which movement is continued to the end of the stroke when the arm 68^a of the starting switch moves downwardly to engage the contact 68^c. It is here assumed that the actuation of the switch 138 will only temporarily close the circuit as hereinafter explained in connection with the work holder shown in Figs. 49 to 52.

The controller 139 also comprises a contact 139^d which may be utilized to bring about automatically a continuous series of forward and reverse strokes of the tool 65. When that mode of operation is desired, the arm 139^a of the switch is swung over into engagement with the contact 139^d, thereby closing a circuit from the conductor 150 through the conductor 151 and the contact arm 139^a to a conductor 159 which leads to the conductor 158. With this arrangement, and assuming the pistons 123 to be in their upper positions, the circuit of the solenoid-operated valve 133 is completed from the line conductor 144 through the conductor 143 to one terminal of the solenoid and then from the other terminal of the solenoid through the conductor 142, the switch 68, conductor 141, conductor 158, conductor 159, switch 139, conductor 151, conductor 150, switch 69, conductor 149, switch 148 and the conductor 147 to the other line conductor 145. This connection initiates the downward stroke which is continued by the movement of the switch arm 68^a into engagement with the switch contact 68^c and at the end of the stroke the switch arm 68^a engages the contact 69^c to establish the circuit of the exhaust solenoid-operated valve 135, whereupon the reverse stroke is automatically initiated. When the pistons have been restored to their initial upper positions, the circuit conditions shown in Fig. 20 are re-established so that another forward stroke is immediately executed. This arrangement may be desirable when operating upon small pieces

in place on the work holder between successive downward strokes of the rotating drill.

In addition to the circuit connections which have just been described, the compressed air system and the electric circuit also include means for actuating a pressure-operated work holder adapted to grip the work during the drilling operation. This apparatus includes a solenoid-operated valve 165 for controlling the admission of compressed air to the work holder, and another solenoid-operated valve 166 for controlling the exhaust of compressed air from the work holder. These solenoid-operated valves include a valve block 167 through which compressed air is conveyed from the metering block 131 through a pipe 168 and, from the block 167, another pipe 169 leads to the work holder. In Fig. 20 this pipe is not shown as being connected to the work holder because the work holder there illustrated is not one of the type adapted to be actuated by compressed air but such work holders are shown in Figs. 46 to 52, inclusive. These solenoids for controlling the actuation of a fluid pressure work holder are controlled by an auxiliary switch 170 which is mounted on the machine for actuation by the movement of the drill toward and from the work. This switch comprises an arm 170^a which is carried by or movable with the pressure platen 110 and which is permanently connected by a conductor 171 through a manually-operated switch 172 with the line conductor 145. When the pistons 123 and the pressure platen 110 are in their upper positions, the arm 170^a of the auxiliary switch engages the upper contact 170^b which is connected by a conductor 173 with one terminal of the solenoid 166, the other terminal of this solenoid being connected by a conductor 174 with the other line conductor 144, thus completing the circuit of the exhaust solenoid 166 to open the exhaust valve when the pistons are in their upper positions, thereby allowing the compressed air in the holder or fixture to exhaust to the atmosphere through a pipe 175 carried by the block 167. As the pressure platen 110 moves downwardly, the switch arm 170^a is carried downwardly until it engages a switch contact 170^c, thus breaking the circuit of the exhaust solenoid 166 and establishing a circuit from the contact 170^c through a conductor 176 to one terminal of the solenoid 165, the other terminal of this solenoid being connected by a conductor 177 with the previously described conductor 174 leading to the line conductor 144. When the solenoid 165 is thus energized, compressed air is admitted through the pipe 168 to the block 167 and it then flows through the pipe 169 to the work holder, causing the work holder to be actuated to grip the work piece. This work piece is then held securely by the action of compressed air until the pressure platen 110 again returns to its upper position and causes the switch arm 170^a to engage the contact 170^b and thereby energize again the exhaust solenoid 166.

When the operator initiates a downward stroke of the pistons 123 and of the tool 65 by actuating the foot pedal switch 137 or the piece part control switch 138, that movement of the pistons and of the drill continues in the manner above described until, at the end of the downward stroke, the circuit connections are automatically reversed to bring about a return stroke of the pistons and of the tool. As the pistons approach the lower limit of their travel, the greater air pressure acting upon the upper sides of the pis-

tons may cause further compression of the lower air pressure which acts upon the lower sides of these pistons, having effective areas less than their upper sides due to the piston rods, thus effecting a further compression of this pressure on the lower sides of the pistons and cushioning the stroke of the tool as it approaches the end of its downward stroke. The compressed air acting on the upper sides of the pistons moves the tool with a yielding pressure which allows the movement of the tool to be retarded when unusual resistance is encountered, with a consequent further compression of the applied air. The extent of this cushioning action will depend upon the relative values of the air pressures which are employed on opposite sides of the pistons 123 and also upon the amount of leakage of compressed air which may take place from the spaces beneath the pistons as these pistons approach the bottoms of the cylinders. In practice, it has been found that with a supply pressure of 90 pounds per square inch, satisfactory operation may be obtained with the constantly acting back pressure adjusted to about 14 or 15 pounds per square inch and with the operating pressure applied to the upper sides of the pistons adjusted to some value between 20 pounds and 75 pounds per square inch. In addition to this cushioning action effected by air pressure alone, provision is made for automatically retarding and eventually arresting the movement of the pistons 123 of the tool by the dash-pot mechanism heretofore referred to. This dash-pot mechanism is illustrated particularly in Figs. 1, 2, 3, 5, 7, 8, 9, 10, 11 and 12 and it is carried by the valve block 66 which is attached to the front face of the cylinder block 67 by screws 179, as shown particularly in Fig. 7. The valve block 66 has formed therein a cylinder 66^c in the lower end of which there is mounted a cylindrical cage-like member 180 comprising a cylindrical bottom portion 180^a connected by oppositely extending webs 180^b, shown in Fig. 9, with a transverse portion 180^c from which a sleeve 180^d extends upwardly. The sleeve portion 180^d and the transverse part 180^c are provided with a cylindrical bore in which there is mounted a cylindrical dash-pot plunger 181. The member 181 extends above the upper end of the sleeve 180^d and is provided at its upper end with an outwardly extending flange 181^a. A coil spring 182 is mounted around the sleeve 180^d and around the upper end of the plunger 181 and this spring serves normally to maintain the plunger in its uppermost position, shown in Fig. 8, the upward movement of the plunger being limited by a transverse pin 183 mounted in the lower end thereof and adapted to engage the underside of the transverse portion 180^c. The cylindrical chamber 66^c is adapted to be partially filled with a body of oil 184 or other substantially incompressible fluid and the bottom portion 180^a of the member 180 is provided with a well 180^e, the outer annular wall 180^f of which is enlarged toward its upper end so that the wall has a slight taper. When the dash-pot plunger 181 moves downwardly from the position shown in Fig. 8 to the position shown in Fig. 11, it is adapted to enter the well 180^e and thus trap a part of the oil which is contained therein. A part of the oil is adapted to pass out around the lower end of the plunger but, as the plunger continues its downward movement, the tightness of the fit between the plunger and the annular wall 180^f increases and the plunger 181 is eventually brought to rest.

In order to make use of the above-described

15

action of the dash-pot plunger 181 for retarding the downward movement of the pressure platen 110 and eventually arresting that movement, which is desirable in order to prevent the tool 65 from breaking suddenly through the work piece at the end of the drilling operation, connections are provided for causing the plunger 181 to be moved downwardly by the pressure platen as it nears the predetermined lower limit of its stroke. For this purpose, there is provided 10 a vertically slidable actuating rod 185 having an enlarged cylindrical upper portion 185^a which is adapted to slide in a cylindrical bore 66^d formed in the valve block 66. The upper end of the portion 185^a has mounted thereon a transverse arm 186 which extends over and is adapted to engage the upper reduced extremity 181^b of the plunger 181. When a downward pull is exerted upon the rod 185, the dash-pot plunger 181 is forced downwardly against the compression of the spring 182, thereby causing the lower end of the plunger to trap a portion of the oil in the well 180. When the rod 185 and the arm 186 are moved upwardly, the plunger 181 is permitted to return to its normal upper position, shown in Fig. 8, by the action of the spring 182.

The front face of the block 66 is recessed as shown at 66^c in Fig. 8 and the rod 185 which extends through this recess is provided on its rear side with a square shouldered notch 185^b fitted by a transverse bar 188. This bar is secured in the notch by a screw 189 passing through a hole in the rod. When the bar 188 is in its extreme positions there is a clearance between the bar and the upper and lower walls of the recess 66^c, so that the recess does not restrict the freedom of movement of the bar 188 and the rod 185. The rod is threaded below the block 66 as shown at 185^c and this threaded portion loosely engages an aperture in an arm 190 which projects laterally from a vertical actuating rod 191 fixed in a boss 110^l formed in the pressure platen 110 as shown in Fig. 3. The arm 190 is adapted to actuate the rod 185 through the agency of a pair of lock nuts 192 secured in adjusted position on the shaft above the arm and by a knurled nut 193 engaging the shaft below the arm. By adjusting these nuts the rod 191 may be caused to actuate the rod 185 in either direction and thus operate the dash-pot mechanism and return it to its normal condition at the desired points in the stroke which will depend upon the depth of the hole being drilled. As explained hereinafter, these movements of the rod 185 are utilized also for actuating the operating switch 69 at the desired point in the downward stroke to change the circuit connections and cause a reverse stroke to take place.

Having described the general operation of the system and the means for retarding the movement of the tool at the end of the stroke, a more detailed description of certain parts of the apparatus will now be given, referring first to the parts of the fluid pressure system. The mechanism for regulating the air pressure and controlling the admission and exhaust of this pressure are shown particularly in Figs. 21 to 35, inclusive, where the main supply pipe 130, leading from an air compressor or the like, is shown as communicating with an internal chamber 131^a in the metering block 131. The compressed air from the chamber 131^a flows upwardly through a short pipe 195 to the pressure regulator 88 from which the air at a regulated pressure passes upwardly through the pipe 196 to the pressure gauge 90. From the rear

16

of this gauge the air at the regulated pressure passes downwardly through the pipe 152 (see Figs. 25 and 31) to a passage 131^d in the block 131 which leads to the valve chamber 131^b in which is mounted a tubular valve member 197 forming a part of the solenoid operated valve 133. The member 197 is mounted in an aperture 131^c which is normally closed at its lower end by a plug 198. The member 197 has a tubular bore therethrough comprising a larger passage 197^a in its upper part communicating with a smaller bore 197^b in its lower part, thus forming an annular shoulder 197^c which forms a valve seat for the conical valve member 133^a which is carried at the lower end of the valve stem 133^b. The wall of the member 197 is apertured, as shown at 197^d, to permit the free flow of air about the valve member 133^a.

The solenoid operated valve 133 is illustrated particularly in Figs. 24 and 31, where it is shown as comprising a solenoid 133^c enclosed within a casing 133^d and having a tubular core 133^e in which is mounted a metal sleeve 199 formed integrally with a hexagonal nut 199^a and an annular threaded part 199^b which is adapted to be threaded into the threaded aperture which forms a continuation of the chamber 131^b in the block 131. The sleeve 199 has slidably mounted therein a cylindrical piston 200 provided at its lower end with a tubular bore 200^a closed at its bottom by a headless nut 201 provided with a central bore in which the valve stem 133^b is slidably mounted. The chamber formed by the bore 200^a is somewhat longer than the vertical dimension of the head 133^c of the valve stem so that the valve member 133^a has a limited vertical movement with respect to the piston 200. Compressed air admitted to the chamber 131^b of the metering block is permitted to pass upwardly around the piston 200 so that there is some atmospheric pressure on both sides of this piston and, under normal conditions, the piston 200 drops by gravity with the upper wall engaging the head 133^c and causing the cone-shaped valve member 133^a to engage its seat in the valve member 197. When the solenoid 133 is energized by the closing of the foot pedal switch 137 or the piece part control switch 138, for example, the piston 200 which is formed of magnetizable material is drawn upwardly by the solenoid and the head 133^c is engaged by the nut 201, thus lifting the valve 133^a from its seat and permitting the compressed air to flow downwardly through the passage into the lower part of the valve member 197 and into the chamber 131^c which is closed at its bottom by the plug 198. The sleeve 199 is closed at its upper end by an end wall 199^c which has formed integrally therewith a stud 199^d arranged to extend through a hole in the casing 133^d of the solenoid and engaged on its upper side by a nut 202. A coil spring 203 is mounted between the solenoid 133^c and the top wall of the casing, thus holding the casing in fixed relationship to the solenoid.

When the valve 133^a is moved to its open position by the actuation of the solenoid, compressed air is permitted to flow from the chamber 131^c below the valve through a passage 131^e, shown particularly in Figs. 30, 31 and 32, which extends horizontally at its upper end and is engaged by the tapered extremity 92^a of the metering screw 92 previously referred to. The body portion of this screw loosely engages a larger passage 131^f which is in alignment with the upper portion of the passage 131^e, as shown in Fig. 32, 75 and the threaded extremity of this screw, which is

flattened at its end for engagement by a wrench, threadedly engages an externally threaded sleeve 104 which is mounted in a threaded recess in the block 131 and which engages a packing gland 205 to form a fluid tight joint about the stem of the metering screw 92. By adjusting the metering screw, the rate of flow of compressed air from the passage 131^a to the passage 131^c may be regulated to control the speed of movement of the pistons 123 downwardly in their cylinders. From the passage 131^c, the compressed air flows upwardly through a small port and into a horizontal passage 131^b which is formed in the metering block and which has the form illustrated particularly in Figs. 30, 31 and 34. The compressed air flows through this passage 131^b to the transverse passage 131^d where it is engaged by the nipple 206 which forms a connection with the supply pipe 127 by which the compressed air is conveyed to the upper ends of the cylinders 123, as heretofore described. At the same time compressed air flows from the passage 131^b and fills a part of the exhaust passage, hereinafter described, as far as the port which is closed by the solenoid operated exhaust valve 135, so that when that valve is subsequently opened, and the valve 133 closed, the air in the upper parts of the cylinders may be exhausted.

The block 131 also contains or carries the means for controlling the supply of compressed fluid through the pipe 125 to the lower ends of the cylinders 67^c. For this purpose the metering block 131 is provided, adjacent the place where the supply pipe 130 communicates with the chamber 131^a, with a transverse opening threadedly engaged by a pipe 208 which communicates with the pressure regulator 89 by which the back pressure adapted to effect the reverse strokes of the pistons 123 is regulated so that it is always lower than the pressure which is regulated by the regulator 88 for producing the downward strokes of these pistons. From the pressure regulator 89 the compressed air flows upwardly through a pipe 209 to the pressure gauge 94, previously referred to, and from this pressure gauge a direct connection is made with the pipe 125 through which the compressed air is conveyed to the lower ends of the cylinders 67^c.

When the pistons 123 reach the bottoms of their strokes and thereby move the arm 69^a of the operating switch 69 to its lower position, thus energizing the exhaust solenoid 135, as previously described, the solenoid 133 is deenergized and the valve member 133^a moves to its closed position by gravity so that the back pressure in the lower ends of the cylinders 67^c then moves the pistons 123 upwardly and, at this time, the air pressure in the upper ends of the cylinders 67^c is permitted to exhaust through the pipe 127 and through the metering block 131 which is provided with the metering screw 93 for controlling the rate of this exhaust. The air being exhausted, being unable to flow outwardly by the passages through which it entered because of the closing of the valve member 133^a, flows through the passage 131^c and thence downwardly through a small port, shown in Figs. 33 and 34, into a passage 131^d which is loosely engaged by the stem of the metering screw 93. This stem has a threaded engagement with a sleeve 211 which in turn threadedly engages a recess in the wall of the block 131 and which compresses a packing gland 212 to form a fluid tight joint. The outer end of the metering screw is flattened for engagement by a wrench

or the like and the inner end is provided with a cone-shaped portion 93^a which regulates the flow of air from the passage 131^d to a passage 131^b of smaller diameter which connects with a downwardly directed passage 131^c. The latter passage communicates through a threaded nipple with the pipe 134 through which the air being exhausted is conveyed downwardly to the block 161 of the solenoid operated exhaust valve 135 which controls the exhaust of the air to the atmosphere through the pipe 136. The solenoid operated exhaust valve 135 is shown particularly in Fig. 40 and comprises a cone-shaped valve member 135^a carried at the end of a valve stem 135^b. The structure of the solenoid and its associated parts by which the valve member 135^a is actuated are the same as the corresponding parts of the solenoid operated valve 133 and the description need not be repeated. The solenoid operated valve 135 comprises a similar sleeve provided at its lower end with a hexagonal portion 213^a and a threaded part 213^b which engages the threaded upper end of the chamber 161^a which is formed in the block 161. The valve member 135^a normally occupies a position on a seat formed by a valve member 214 which is mounted in the chamber 161^a with its lower reduced portion entering a chamber 161^b which communicates through an elbow 215 with the exhaust pipe 136. The block 161 is secured by a screw 216 to the front wall of the housing 55 and the pipe 134 communicates with the chamber 161^a through an aperture in the rear wall of the block 161. When the air being exhausted flows to the chamber 161^a through the pipe 134 at a rate controlled by the adjustment of the exhaust metering screw 93, the valve member 135^a is lifted due to the energization of the solenoid of the valve 135 at that time, thus permitting the air to flow through the valve member 214 and downwardly through the pipe 136. When the pistons 123 reach the upper ends of their strokes, the switches 68 and 69 are restored to their initial positions, shown in Fig. 20, thus deenergizing the exhaust solenoid valve 135 which is then restored to its closed position shown in Fig. 40 by gravity.

When a work holder is employed which is adapted to hold the work piece by the pressure of compressed air or the like, the supply of compressed air for this purpose is conveyed from the metering block 131 through the pipe 168 to the block 167 on which the intake solenoid valve 165 and the exhaust solenoid valve 166 are mounted, as heretofore explained in connection with Fig. 20. These solenoid-operated valves 165 and 166 are illustrated particularly in Figs. 39 and 41 and the pipe 168 which supplies compressed air thereto is supplied with unregulated compressed air through a nipple 217 communicating with the bottom of the chamber 131^a of the metering block 131, as shown in Fig. 29. This pipe 168 communicates through the side of the block 167 with a chamber 167^a in which is mounted a tubular valve member 218 having an annular seat engaged by the conical valve member 165^a of the solenoid-operated valve 165 which is mounted on the block and has a threaded portion engaging the upper end of the chamber 167^a, as in the forms of construction previously described. The valve member 165^a is carried by a stem 165^b and the other parts of this solenoid-operated valve are like those of the valve 133. The passage 218^a in the lower part of the valve member 218 communicates through the passage

167^b in the valve block which is closed at its lower end by a plug 219 and which communicates with a lateral passage 167^c. The block 167 is formed of two hexagonal parts attached together and the passage 167^c is formed partly in each hexagonal block, the two portions of the passage being connected through a sleeve 220. The passage 167^c communicates with a chamber 167^d which is formed in the block beneath the solenoid-operated valve 166, being closed at its upper end by a threaded portion of that valve, as in the forms of construction previously described. There is mounted in the chamber 167^d a tubular valve member 221 which is similar to the corresponding valve member of the solenoid-operated valve 133, and this valve member 221 has an annular seat which is normally engaged by a conical valve member 166^a carried by a valve stem 166^b. The passage 221^a leading downwardly through the valve member 221^a communicates with a chamber 167^e which is threadedly engaged by a nipple 222 through which a connection is established with the pipe 175 by which the air is exhausted to the atmosphere. The pipe 169, through which the compressed air is supplied to the work holding fixture, communicates through a nipple 223 with the chamber 167^d, as shown particularly in Fig. 41. When the circuit of the solenoid-operated valve 165 is closed by the downward movement of the pressure platen 110 to a point where the arm 170 engages the switch contact 170^c, the valve member 135^a is raised from its seat, thus permitting compressed air to flow from the pipe 168 through the chamber 167^a, valve member 218, and passage 167^c to the chamber 167^d, from which it flows directly through the pipe 169 to the work holding fixture. The work piece is then held by the fixture during the downward stroke of the drill 65 and throughout the upward stroke of the tool and the pressure platen until the pressure platen 110 reaches its normal position shown in Fig. 20, whereupon the switch arm 170 engages the contact 170^b and thereby causes the exhaust solenoid-operated valve 166 to be energized. In the meantime, the solenoid-operated valve 165 will have been deenergized by the disengagement of the arm 170^a and the contact 170^c and the valve member 166^a of the exhaust solenoid valve will then be elevated so that the air in the work holding fixture will then be permitted to exhaust to the atmosphere through the pipe 175.

In the compressed air system which has just been described, the pressure regulators 88 and 89 may preferably have the form shown particularly in Fig. 35. The two regulators may be alike and a description will therefore be given only of the regulator 88 which controls the pressure of the fluid by which the pistons 123 are moved on their downward strokes. Each pressure regulator comprises two casings 232 and 233 which have threaded engagement with each other and which are adapted to clamp between them a resilient diaphragm 234. A plate 235 is mounted on one side of the diaphragm and a coil spring 236 is positioned between this plate and a collar 237 which is mounted on one end of an adjusting screw 238. This adjusting screw threadedly engages the end of the casing 233 and has a handle 238^a which permits the screw to be turned to regulate the compression of the spring 236. A lock nut 239 may be used to secure the screw 238 in adjusted position. In this manner, it is possible to regulate the initial compression of the spring 236 which must be overcome by the out-

ward movement of the diaphragm 234 under the influence of the compressed air which is admitted to the pressure regulator through the pipe 195 (or 208). A disk 240 is secured to the face of the diaphragm 234 opposite the plate 235 and this disk is connected by a valve stem 241 with a valve member 242 which is adapted to control the admission of compressed air through the port 232^a into the chamber 233^a adjacent the diaphragm. The valve member 242 carries a block 243 which is recessed on the side opposite the valve member 242 to receive the end of a coil spring 244 capable of being adjusted by a threaded plug 245 which has a threaded engagement with an aperture formed in the end of the casing 242. By adjusting this plug, the compression of the spring 244 may be varied to regulate the pressure with which it normally causes the valve member 242 to engage its seat around the port 232^a. The compressed air which is supplied through the pipe 195 (or 208) is admitted through a port 232^b to the chamber 233^b which is formed in the casing 232 on the inlet side of the valve member 242.

The back pressure in the pipe 196 (or 209) 25 communicates with the chamber 233^a, adjacent the diaphragm, through a port 232^c. When this back pressure falls as the result of the flow of compressed air to the valve block 66, the diaphragm 234 is moved by the spring 236, causing the valve 242 to open the port 232^a and thereby admit additional compressed air from the supply pipe 195 to the chamber 233^a adjacent the diaphragm. The diaphragm is then moved against the compression of the spring 236, which causes the valve 242 to be moved again to its closed position. This additional supply of compressed fluid which is thus admitted to the chamber 233^a passes through the pipe 196 and the pressure gauge 90 from which it flows through the pipe 152 and the connected passages in the metering block 131 to the pipe 121 by which it is conveyed to the cylinders 67^c. By suitably adjusting the springs 236 and 244 of the pressure regulator, the frequency and extent of opening of the port 232^a by the valve 242 may be regulated in order to maintain any desired pressure of the air which is supplied to the upper ends of the cylinders 67^c. In a similar way, the adjustment of the springs of the pressure regulator 89 may be utilized to secure any desired 40 degree of the pressure which is conveyed through the pipe 125 and its branches to the lower ends of the cylinders 67^c.

In order to prevent any building up of the pressure in the upper ends of the cylinders 67^c, when 55 it is intended that the machine be idle, which might result in an accumulation of pressure to the point where the pistons 123 would be actuated to produce a downward stroke of the tool, and which might arise from leakage caused by dust on the seat of the regulating valve 88, for example, there is provided in the block 66 a chamber 66^c, shown in Fig. 17, which communicates through a port 66^a with the passage 66^b to which compressed fluid is supplied by the pipe 127. The chamber 66^c communicates with the atmosphere through a port 66^d and the flow of fluid through the ports 66^a and 66^d to the atmosphere is controlled by a needle valve 246 which has a threaded engagement with the lower end of the chamber 66. This needle valve may be adjusted so that there will be a small leakage at all times from the chamber 66^a and the pipe 127. This leakage will not interfere with the proper operation of the machine when it is intentionally actuated but will 60 prevent any building up of the pressure on the 65 chamber 66^c. This needle valve 246 may be adjusted so that there will be a small leakage at all times from the chamber 66^a and the pipe 127. This leakage will not interfere with the proper operation of the machine when it is intentionally actuated but will 70 prevent any building up of the pressure on the 75 chamber 66^c.

upper ends of the pistons 123 when the machine is idle.

The starting switch 68, the operating switch 69, the foot pedal switch 131, the safety switch 148 and the auxiliary switch 170 may all be of substantially the same construction and a detailed description will therefore be given of the starting switch 68 which is illustrated in detail in Figs. 13 to 16, inclusive. This switch comprises an insulating block 248, formed of Bakelite or other molded insulating material, which has a removable cover 248^a and an internal chamber 248^b in which the principal parts of the switch mechanism are mounted. The movable contact arm 68^a of this switch is secured at one end to a block 249 which is fixed to a terminal post 250 mounted in the wall of the switch casing and comprising a sleeve 250^a and two screws 250^b and 250^c. The upper screw 250^c secures in place a terminal clip 142^a which is soldered or otherwise connected to the end of the conductor 142 previously described. The movable arm 68^a is provided with lateral bowed portions 68^d which have their free extremities interlocked with notches formed in the ends of arms 249^a which are formed in the block 249, thus giving the resilient arm 68^a additional tendency to move downwardly so that the contact member 68^e carried at its free extremity will normally engage the stationary contacts 68^c. This contact 68^c is in the form of an L-shaped plate having one arm extending transversely of the chamber 248^b and having the other arm extending longitudinally to be secured to a terminal post 252 by means of a screw 252^a. The other end of this terminal post, which is embedded in the wall of the casing 248, is secured by a screw 252^b to a spring clip 153^a attached to the conductor 153 previously described. When the resilient arm 68^a of this switch is moved upwardly away from the contact 68^c, it is adapted to engage the stationary contact 68^b which is also in the form of an L-shaped plate having one arm extending parallel to the contact arm 68^c and having the other arm engaged by a screw 253^a which secures it to a terminal post 253^b embodied in the wall of the casing. This terminal post is engaged by a screw 253^c which secures it to a terminal clip 141^a attached to the conductor 141.

The movement of the arm 68^a of the switch 68 away from the contact 68^c and in opposition to its own resiliency, is effected by a plunger 255 having an enlarged head 255^a, located within the casing 248, which is adapted to engage the underside of the contact arm 68^a and having a reduced stem portion which is mounted to slide in a sleeve 256 embodied in the removable cover 248^a of the switch casing. The projecting end of this plunger 255 is adapted to be engaged by the upper side of the horizontal bar 188, shown in Figs. 17, 18 and 19, which, as previously described, is moved vertically by the rod 185 by which the dash-pot mechanism is actuated. Since the rod 185 is actuated by the arm 190 and the rod 191 which are mounted on the platen 110, the movements of the rod 185 are utilized not only for controlling the dash-pot mechanism but for controlling the actuation of the starting switch 68 and the operating switch 69 at the proper points in the travel of the tool 65. Thus, when the pistons 123 are at the upper limits of their strokes, the bar 188, carried by the rod 185, engages the plunger 255 and moves the arm 68^a of the switch 68 so that it passes out of engagement with the stationary contact 68^c into engagement with the stationary contact 68^b, as heretofore described in connection with the ex-

planation of Fig. 20 and the general mode of operation of the machine. Also, when the pistons 123 are at the upper limits of their strokes, the rod 185 is carried upwardly to such an extent by the rod 191 and the arm 190 that the arm 186, mounted on the upper end of the rod 185, is positioned above the upper end 181^b of the dash-pot plunger, leaving a clearance 186^a. Then, when the downward stroke of the pistons 123 is initiated, either by operating the foot pedal switch 131 or the piece part control switch 138, the arm 190 and the rod 191 carried by the pressure platen move downwardly and allow the rod 185 and the arm 188 to drop by gravity to the extent of the clearance 186^a so that the bar 188 carried by the rod 185 releases the plunger 255 of the switch and allows the switch arm 68^a to move downwardly due to its own resiliency and establish contact with the stationary contact member 68^c. The bar 188 which actuates the plunger 255 of the switch 68 also actuates the plunger 257 of the switch 69 through an intermediate actuating rod 258, of cylindrical form, which slides in a cylindrical bore 66ⁱ formed in the block 66, as shown in Figs. 17, 18 and 19. A pin 259 is secured in the bar 188 and projects rearwardly through a slot 66^j in the block 66 to engage a notch 258^a which is formed in the side of the rod 258. This rod also has another notch 258^b milled in its side for engagement by a stop member 260 which slides within a tubular bore 66^k formed in the block 66 and which is pressed against the member 258 by a coil spring 261 mounted in this tubular bore and held under the proper degree of normal compression by an adjustable plug or screw 262. This stop member 260 is pressed against the rod 258 so that the rod retains its position against the force of gravity unless positively moved by the pin 259 mounted on the bar 188. The notch 258^b is sufficiently long to permit the required amplitude of movement of the rod 258 when this rod is actuated and the vertical dimension of the notch 258^a is substantially greater than the diameter of the pin 259 so that there is some lost motion in this connection which necessitates a substantial degree of movement of the bar 188 before the switch operating rod 258 is actuated. Thus, when the pistons 123 and the tool 65 are moved downwardly by the action of the compressed air, the arm 190 carried by the actuating rod 191 moves freely on the rod 185 until the tool nears the end of its downward stroke, whereupon the arm 190 engages a knurled nut 192 on the rod 185 and pulls this rod downwardly to actuate the dash-pot mechanism heretofore described, thus retarding the movement of the tool at the end of its stroke. When the rod 185 is thus moved downwardly, the bar 188 is carried with it and, after a predetermined movement, the pin 259 engages the bottom of the notch 258^a and moves the rod 258 downwardly in its bearing so that the plunger 257 of the switch 69, which rests upon the upper end of the rod 258 is permitted to move downwardly under the influence of the resiliency of the movable switch arm 68^a so that this arm then moves out of engagement with the contact 68^b and into engagement with the contact 68^c to effect the deenergization of the solenoid operated switch 133, the energization of the exhaust solenoid valve 135, and the resulting exhaust of the compressed fluid above the pistons 123 to the atmosphere, so that the pistons then execute a return stroke under the influence of the compressed air which is constantly applied to the undersides of the pistons 123. Due to the lost

motion provided by the elongated slot 258^a, the operation of the dash-pot mechanism begins before the rod 258 is actuated to reverse the connections of the switch 69, thus allowing the dash-pot mechanism to become effective in retarding the movement of the pistons and the tool before the downward movement is arrested by the operation of the switch and the change in the circuit connections. After those circuit connections have been changed as just described, through the engagement of the pin 259 with the bottom of the notch 258^a, the rod 185 and the switch operating rod 258 will remain in the lower positions to which they have just been moved during the return strokes of the pistons 123 and the tool 65 until the arm 190 engages the lower nut 192 on the rod 185, whereupon the rod is again moved upwardly carrying with it the bar 188 and the pin 259 which, after the pin has taken up the lost motion provided by the slot 258^a, again moves the switch operating rod 258 to its upper position and causes it to move the switch operating plunger 257 upwardly to restore the circuit condition in the switch 69 which is shown in Fig. 20. By suitably adjusting the positions of the nuts 192 and 193 on the rod 185, the operator may thus regulate correctly the point at which the dash-pot mechanism is brought into play to retard the movement of the tool at the end of its stroke and, also, to control the actuation of the switches 68 and 69 for causing the downward stroke of the pistons to terminate and their reverse strokes to begin at a predetermined point in the travel of the tool 65. In this way, the direction of movement of the tool may be reversed as soon as it has passed through the work or it may be reversed after a blind hole of predetermined depth has been drilled.

The foot pedal switch 137 and the safety switch 148 are embodied in the foot pedal device 85 previously referred to which is illustrated more particularly in Figs. 37 and 38 and which comprises a hollow casing 265 adapted to rest upon the floor adjacent the other parts of the machine and having an inclined top wall 265^a provided with a serrated surface to be engaged by the heel portion of the foot of the operator. The forward portion of the casing is provided with a pair of upwardly extending ears 265^b in which there is pivotally mounted by means of a pin 266 a foot lever 267 adapted to be engaged by the ball of the foot for tilting the lever either forwardly or rearwardly about the intermediate pivotal pin 266. The switches 137 and 148, which are generally similar to the switch 68 previously described except that only one stationary contact of the switch 137 is used, are mounted in the chamber 265^c of the casing 265 with their operating plungers 268 and 269, respectively, directed upwardly. The casing is provided with two tubular bores 265^d and 265^e in which are mounted the cylindrical plungers 270 and 271, respectively. These plungers have rounded upper ends and are engaged by the hard metal plates 272 and 273, respectively, which are secured in the underside of the lever 267 on opposite sides of its pivot. The plunger 270 has a stem 270^a of reduced diameter which is adapted to engage the plunger 268 of the switch 137 and the plunger 271 has a stem 271^a of reduced diameter which is adapted to engage the plunger 269 of the switch 148. A coil spring 274 is mounted in each of the bores 265^d and 265^e to cause the plungers 270 and 271 to be moved normally upward into engagement with the plates 272 and 273 of the foot lever.

With this construction, the foot lever 267 normally occupies the position shown in Fig. 37 which corresponds to the relative positions of the switch contacts illustrated in Fig. 30 with the switch 137 open and the switch 148 completing a circuit between the conductors 147 and 149. When the operator wishes to start the machine through the actuation of the foot pedal device, he presses downwardly on the lever 267, causing it to rock rearwardly about the pivot 266 and thus actuating the switch plunger 268 to close the contacts of the switch 137. When it is desired to arrest the operation of the machine because of some emergency, as heretofore described, the operator rocks the foot pedal lever 267 forwardly and thus actuates the switch 148 through the plunger 269 to cause the switch arm 148^a to move downwardly out of engagement with the contact 148^b and into engagement with the contact 148^c. The conductors 140, 141, 147, 149 and 156 may conveniently be located within a flexible conduit 86 which extends from the foot pedal device 85 to the interior of the housing 55.

One form of the work holder or fixture 60 which is illustrated in Figs. 1, 2 and 20 is shown in further detail in Figs. 42 to 45, inclusive. This fixture comprises an upright frame or standard 280 having a transverse base flange 280^a which is secured to the work table 57 by the studs 61. Adjacent its upper end, this standard is provided with a forwardly directed flange 280^b reinforced by the vertical flanges 280^c and provided at its forward edge with an inwardly extending U-shaped slot 280^d. On the upper side of this supporting flange 280^b and seating against an upright shoulder 280^e, located toward the rear part thereof, is a plate 281 which is secured to the flange 280^b by screws 282. On the upper side of the plate 281 there is mounted a retaining or stripper plate 283 secured in place by pins 284 and screws 285. This plate has an overhanging flange 283^a spaced upwardly from the plate 281 and overhanging the transverse groove 281^a which is formed in the upper side of the plate 281. From the bottom of this groove, an aperture 281^b extends downwardly through the plate 281 in alignment with the notch 280^d formed in the flange 280^b and this aperture 281^b is in alignment with a similar aperture formed in the overhanging flange 283^a of the upper plate. A sleeve or drill bushing 286 is mounted in this aperture of the flange 283^a and it has a bore which is adapted to be engaged with a free sliding movement by the tool 65 carried by the pressure platen of the machine.

When the tool 65 is moved downwardly in its operative stroke it is adapted to pass through the bushing 286 and to engage the work piece 58 which is adapted to fit within the groove 281^a formed in the holding plate 281. The walls of this groove may be formed to diverge outwardly at their forward ends, as shown in Fig. 43, to facilitate the insertion of the work piece which, in this instance, is in the form of a small angular plate adapted to have holes drilled in its right-angularly disposed arms when it has been fully inserted into the groove 281^a with its right-angularly disposed arm engaging the front edge 281^c of the plate 281. In order that the insertion of the work piece 58 to the operative position may be utilized to start the operation of the machine and the downward movement of the drill, as heretofore described, the piece part control switch 138 is mounted in the chamber 280^c of the standard 280, as shown in Fig. 45. The movable arm 138^a

of this switch is adapted to be actuated by a plunger 288 and the switch may be constructed like switch 68 previously described except that only one stationary contact 138^b is utilized, the two contacts 138^a and 138^b being connected to the conductors 157 and 158 which may preferably be located in a flexible conduit 289 leading from the interior of the housing 55 to the chamber 280^e of the standard 280. The plunger 288 of the switch 138 is adapted to be actuated by a resilient arm 290 which has one end secured to the cover of the switch housing and which has its other end apertured for engagement by a switch operating rod 291 which is mounted to reciprocate in the upper part of the standard 280. The rod 291 has a cylindrical enlargement 292 which slides in a bearing in the front wall of the chamber 280^f in which the switch is located. A flange 292^a on this enlargement limits the rearward movement of the switch operating rod 291. The rear end of the rod 291 is slidably mounted in a sleeve 293 which is secured in adjusted position in the rear wall of the chamber 280^e by a set screw 294. A collar 295 is secured by a set screw 296 on the enlargement 292 within the chamber 280^e and a coil spring 297 bearing against the end of the enlargement 292 acts normally to move the rod 291 to its forward position shown in Figs. 43 and 45. When the rod 291 is moved rearwardly, the collar 295 engages the resilient arm 290 and causes it to actuate the switch plunger 288 which is located behind it, thus closing the switch contacts 138^a and 138^b and thereby initiating the operation of the machine through the starting switch 68. The compression of the spring 297 may be varied by adjusting the sleeve 293 and the normal position of the forward end of the rod 291 may be regulated by adjusting the collar 295. The rod 291 is adapted to be engaged at its forward end by the extremity of the arm 58^a of the work piece which slides in the groove 281^a so that, when the work piece is inserted, it will push the plunger 291 rearwardly until, when the work piece reaches its operative position with its lateral arm 58^b engaging the front edge 281^c of the plate 281, the resilient arm 290 will actuate the switch plunger 288. The operator holds the work piece in his fingers during the drilling operation and, when the drilling has been completed and the tool 65 partially withdrawn, he may release his grip upon the work piece, whereupon the plunger 291 will be restored by the spring 297 to its normal position and will at the same time eject the work piece from the work holder, while allowing the switch 138 to return to its open position. The manual release of the work piece, after the drill is withdrawn, is necessary to cause the work holder and the switch 138 to function in this manner. The switch 138 remains closed as long as the work piece remains in the operative position in the holder and, unless the work piece is released, the machine will perform a continuous series of cycles, just as it would if the arm 139^a of the controlling switch 139 were on the stationary contact 139^d. The operation of the machine, with the circuit arrangement shown in Fig. 20, has been explained above on the assumption that the switch 138 would be only temporarily closed by the work piece, as hereafter set forth in the description of Figs. 49 to 52, inclusive.

In Figs. 46, 47 and 48 of the drawings, there is shown a modified form of work holder 300 which is adapted to hold the work piece by pneumatic pressure instead of requiring that it be manually held as in the form just described. The holder

or fixture 300 includes a frame 301 adapted to be secured to the work table 57 and comprising a forwardly extending platform 301^a and an upwardly extending cylinder 301^b. The platform 301^a has a pedestal 302 secured thereon by a screw 303 which passes through a washer 304 from the underside of the platform and engages a threaded aperture extending upwardly in the cylindrical projection 302^a of the pedestal which fits an aperture 301^c formed in the frame. The pedestal 302 is provided at its upper end with a V-shaped groove 302^b in which the work piece 306 is adapted to rest, the extent to which the work piece is inserted being limited by a vertical pin 307 extending upwardly from the bottom of the rear portion of the groove. The frame 301 is provided with bosses 301^d extending laterally from the cylinder 301^b and provided with tubular bores 301^e in which a pair of cylindrical rods 308 are slidably mounted. These rods are connected at their lower ends by a cross bar 309 and the cylinder 301^b is open at its lower end so that the cross bar may be engaged by a cylindrical piston 310 which is mounted to slide in the cylinder 301^b. The upper end portions of the rods 308 engage and fit curved recesses 311^a and 311^b which are formed in a cross head 311. The curved surfaces 311^b are formed in detachable end plates 311^c which are secured to the body portion of the cross head by studs 312, thus clamping the cross head in adjusted position on the rods. The cross head has a forward extension 311^d which is apertured to receive a sleeve 314 having a smaller sleeve or drill bushing 315 fitted therein to receive the drill or other tool 65. The sleeves 314 and 315 are secured in place by a set screw 316 and by changing the sleeves or bushings they may be made of the proper sizes to receive any size of drill. When the drill passes downwardly through the inner bushing 315, it is adapted to engage the work piece 306 held by the pedestal 302.

The upper end of the cylinder 301^b is closed by a cap member or plug 317 which has a threaded engagement therewith and which is provided on its upper side with a circular recess in which is seated the lower end of a coil spring 318. This coil spring extends upwardly and into a recess 311^e which is formed in the underside of the body portion of the cross head 311. The spring 318 thus tends to raise the cross head 311 to its uppermost position wherein the bar 309 is seated against the lower end of the cylinder 301^b, as shown in Fig. 48. With the parts at rest in their normal positions, the piston 310 is in its uppermost position with the cross bar 309 engaging its lower end as well as the lower end of the cylinder 311 and there is then a space 319 between the upper end of the cylinder and the cap 317. This space communicates through a port 301^e with the pipe 169, shown in Fig. 20, by which compressed fluid is conducted from the valve block 167 through which compressed fluid is supplied and exhausted under the control of the solenoid operated valves 165 and 166, as heretofore explained. When the pressure platen 110 moves downwardly to a sufficient extent to cause the switch arm 170^a to engage the contact 170^c, the solenoid operated switch 165 is energized to cause compressed air to be admitted through the pipe 169 to the cylinder 301^b, whereupon the piston 310 is moved downwardly against the compression of the spring 318 to cause the lower enlarged end of the sleeve 315 to engage the upper side of the work piece 306 and hold it securely in place in the V-shaped groove 302^b of the pedestal.

After the drilling of the hole has been completed and the drill 65 has started on its upward stroke, a point is reached where the arm 170^a of the switch 170 becomes disengaged from the contact 170^b, thus deenergizing the solenoid operated valve 165 and permitting the compressed air which has theretofore been supplied through the pipe 169 to the fixture to be exhausted through the pipe 175, this connection being established as soon as the exhaust solenoid valve 166 is opened 5 in response to the completion of its circuit through the engagement of the switch arm 170^a with the contact 170^b. At that time, the pressure on the piston 310 being relieved, the cross head 311 is returned to its upper position by the spring 318 and the work piece 306 may be withdrawn 10 from the fixture. Since this form of work holder does not include a switch for closing the circuit when the work is inserted, it is preferably employed in conjunction with a foot pedal control 15 switch 137.

In Figs. 49 to 52, inclusive, there is shown another form of work holder or fixture 320 which combines certain of the features of the two fixtures heretofore described in that it provides 20 means for gripping the work by fluid pressure and also for actuating the operating circuit in response to the movement of the work piece. In this form, there is provided a frame or block 321 having outwardly extending flanges 321^a which are adapted to be secured to the work table 67 by means of the screws 61. This frame 321 has a tubular bore 321^b formed therein and in this bore there is mounted a hard metal cylinder 322 which is closed at its lower end by an end wall plate 323, having an enlarged body portion which is mounted in a recess in the bottom of the block 321 and held in place by screws 324. A cylindrical piston 325, mounted in this cylinder 322, is provided with a central projection 325^a at its lower end which provides a space 326 between the lower end of the body portion of the piston and the end wall 323 when the piston is in its lowermost position. On the upper end of the piston 325 there is mounted a flat plate 327 which has a straight edge 327^a adapted to travel in proximity to the flat front face of the upright portion 321^c of the frame, thus preventing the piston from rotating. When the piston is in its lower position, the forward portion of the plate 327 rests on a pin 328 which is secured in adjusted position in a hole in the frame or base by a set screw 328^a. A pedestal 329 is mounted on the plate 327 and is secured by screws to the plate and to the piston. This pedestal is provided at its upper end with a V-shaped rearwardly extending groove 329^a adapted to receive the work piece and to move that work piece to operative position when the piston 325 is moved upwardly by fluid pressure admitted through the passages 321^c and 321^d which are adapted to communicate with the supply pipe 169. The upwardly extending portion 321^c of the frame, located at the rear of the cylinder 322, has a horizontal plate 330 secured to its upper end and the forward portion of that plate overhangs the pedestal 329. A tubular sleeve or drill bushing 331 is mounted in the overhanging portion of the plate 330 to receive the drill 65 when this drill is moved downwardly. The work piece 333 is adapted to be seated in the groove 329^a of the pedestal and when the piston 325 is moved upwardly the work piece is held against the lower end of the bushing 331. The stroke of the piston 325 and the corresponding range of movement

of the pedestal 329 may be varied to suit the character of the work by adjusting the position of the stop pin 328.

For the purpose of initiating the operation of the machine by the movement of the work piece, the piece part control switch 138 may be mounted in the rear chamber 321^c of the frame, as shown in Fig. 50, and the resilient arm 290 of this switch is adapted to actuate its plunger 288 in response to the movement of a part which is fixed upon a horizontal rod 335. This switch actuating rod is provided at its forward end with an enlarged head 335^a adapted to engage the work piece, and it is slidably mounted at its rear end in a sleeve 336 which is secured in a part of the frame 321 by a set screw 331. The intermediate portion of the rod 335 threadedly engages a sleeve 338 which is slidably mounted in a bore 321^c formed in the upwardly extending part 321^c of the frame. A nut 339 engages the rod at the end of the sleeve 338 to hold the parts in the proper relative adjustment and the rear end of the sleeve 338 is provided with an outwardly extending collar 338^a which is the part adapted to be engaged by the end of the resilient arm 290 of the switch 138. A coil spring 340 is mounted on the rod 335 between the sleeve 338 and the stationary sleeve 336 so that the sleeve 338 is normally moved to the position shown in Fig. 50 which corresponds to the open position of the switch 138. The compression of this spring may be regulated by adjusting the position of the sleeve 336.

When a work piece 333 is placed on the pedestal 329 by the operator, it is pushed inwardly against the rod 335 until this rod moves inwardly to the extent permitted by the nut 339 and this causes the arm 290 to close the switch 138, thereby completing a circuit through the starting switch 68 and initiating the downward stroke of the pistons 123 and the tool 65. As this downward stroke proceeds, the switch 170 is actuated by the movement of the arm 170^a into engagement with the contact 170^b, thus admitting compressed air through the pipe 169 to the lower end of the cylinder 323. The pedestal 329 and the work piece 333 are then carried upwardly and during this movement the inner end of the work piece engages an inclined face 341^a formed on a block 341 which is secured in the overhanging part 330 of the frame. This block acts as a cam to force the work piece in a forward direction as it is about to be gripped between the pedestal 329 and the bushing 331 carried by the overhanging part 330, thus allowing the rod 335 to move forwardly under the influence of the spring 340 to a sufficient extent to open the piece part control switch 138. This temporary closing of the switch 138 initiates the cycle of operations heretofore explained in connection with Fig. 20 by completing the circuit 60 through the starting switch 68 which changes its position to cause the continuation of the operation after an initial movement of the drill. The drilling operation thus proceeds in the manner heretofore described and, when it is completed, 65 the drill is extracted and the compressed air is automatically exhausted from the lower end of the cylinder 322, thus allowing the piston 325 and the pedestal 329 to return by gravity to their lower positions shown in Fig. 50.

The operation of the apparatus will be understood from the foregoing description and reference will now be made only to some of the more general features of the operation. Having accumulated a supply of work pieces 58 to be placed 75 upon the work support 60, the operator closes the

manually operated switch 146 and also closes the switch 172 in the event that fluid pressure operated means are to be employed for holding the work piece in position during the operation of the tool. The operator then places the work piece in position in the work holder 60 and starts the machine in operation by depressing the rear portion of the foot pedal device 85 to close temporarily the foot pedal switch 137 which establishes a starting circuit through the solenoid operated valve 133 and the starting switch 68. If the work holder 60 is one comprising a switch 138 for closing the operating circuit by the insertion of the work piece into position on the work holder, the operator does not employ the foot pedal switch 137 but closes the starting circuit by inserting the work piece and closing the switch 138. Whichever method of closing the starting circuit is employed, the effect is to actuate the solenoid operated valve 133 to admit compressed air to the upper ends of the cylinders 67^c through the pipe 127, thus causing the pressure platen 110 to move downwardly and carry with it the rotating power driven tool 65. After a limited movement of the pressure platen, the rod 185 drops downwardly to the extent permitted by the clearance 186^a under the arm 186 and thus allows the contact arm 68^a of the switch 68 to move to its lower position and the operator may then release the foot pedal switch 137, which automatically opens. If a piece part control switch of the type shown in Figs. 49 to 52 is employed, this switch will automatically open by the relative movement of the parts of the work holder to the work gripping position and, whether it be the foot pedal switch 137 or the piece part control switch 138 which is thus opened after the machine is started, the operation is continued to cause the completion of the downward stroke, since the circuit of the solenoid operated valve 133 is then continued through the switch 68 and the conductor 153. This downward stroke continues until a point is reached where the switch 69 is actuated by the movement of the rods 191 and 185. The point at which this operation occurs may be adjusted by regulating the position of the nut 193 on the rod 185 so that as the tool 65 approaches the proper depth of a blind hole being drilled or approaches the point where it is about to break through the bottom of an open hole, the rod 185 is actuated to start the operation of the dash-pot mechanism by which the movement of the tool is retarded automatically at the end of its stroke. Due to the lost motion provided by the elongated slot 258^a in the plunger 258, this plunger remains in its uppermost position, held by the spring 261, until a predetermined time after the actuation of the dash-pot mechanism has begun, whereupon the plunger 258 is moved downwardly by the pin 259 which is actuated by the bar 188 mounted on the rod 185, thereby operating the switch 69 to arrest the downward stroke. During that downward stroke, the pistons 123 are moved by the air pressure applied to their upper sides, which is substantially greater than the air pressure which is constantly supplied to the lower sides of these pistons through the pipe 125, and the pistons and the tool are thus moved gradually downward with a yielding pressure which may allow the pistons and the tool to be retarded or arrested in the event that varying or unusual resistance is encountered by the tool. This may bring about additional compression of the fluid which is supplied to the upper sides of the pistons, and as

the pistons approach the lower ends of their strokes the lower pressure air which is supplied to the lower ends of the cylinders may be compressed by the movement of the pistons and may leak outwardly to some extent around the piston rods 120 which extend through the cylinder heads 122. With this arrangement, the pistons 123 are permitted to complete their downward strokes until the downward movement is arrested by the action of the dash-pot mechanism and by the action of the rods 191 and 185 in causing the switch 69 to be actuated so that the arm 69^a thereof moves downwardly into engagement with the stationary contact 69^c, thus establishing a circuit through the exhaust solenoid operated valve 135 which allows the compressed air in the upper parts of the cylinders 67^c to be exhausted to the atmosphere and at the same time allows the pistons 123 to be elevated by the low pressure air constantly applied to the undersides of these pistons. The pressures which are employed to effect the movements of the pistons and the speed with which their downward and upward strokes take place may be controlled by adjusting the regulators 88 and 89 and also by operating the metering valves 92 and 93, previously referred to, so that the speed of movement of the tool 65 may be regulated in accordance with the character of the work being done. If, during the foregoing operations, a work holder is employed which grips the work by pneumatic pressure, the switch 172 may be closed at the commencement of the operation and the actuation of the work holder will then be controlled by the solenoid operated valves 165 and 166 which control the admission of compressed air to and the exhaust of compressed air from the work holder through the pipe 169. If the work being performed is of such a character that the work pieces may be readily inserted and withdrawn, when using a work holder of the type shown in Figs. 42 to 45, for example, the switch 139 may be manipulated to cause the arm 139^a to engage the contact 139^c so that the pressure platen 110 and the tool 65 will then execute a continuous series of forward and reverse strokes with the operator withdrawing a work piece and inserting a new one each time that the tool 65 is in the upper part of its path of travel. In any case, the controlling switch 139 must be adjusted at the beginning of the operation, depending upon whether the operator desires a continuing series of operations of the machine or a succession of manually controlled operations which are initiated either by the foot pedal control switch 137 or by the piece part control switch 138.

Although one embodiment of the invention and several modifications of certain of its parts have been shown and described by way of illustration, it will be understood that the invention may be constructed in various other embodiments coming within the scope of the appended claims.

I claim:

1. The combination in a machine of the class described, of a movably mounted tool, means for moving said tool axially through forward and reverse strokes, a work holder for gripping a work piece, means for causing a forward stroke of said tool, and means actuated by the starting of said forward stroke for causing said holder to grip a work piece placed therein.

2. The combination in a machine of the class described, of a movably mounted tool, means for moving said tool axially through forward and reverse strokes, a work holder for gripping a

work piece, means for causing a forward stroke of said tool, means actuated by the starting of said forward stroke for causing said holder to grip a work piece placed therein, means for arresting said forward stroke and causing a reverse stroke of said tool, and means for automatically causing said holder to release said work piece after said reverse stroke has started.

3. The combination in a machine of the class described, of a movably mounted tool, means for moving said tool axially through forward and reverse strokes, means including an electric circuit for controlling said forward and reverse strokes, a work holder adapted to receive and grip a work piece, means actuated by a work piece in said holder for actuating said circuit to initiate a forward stroke of said tool, and means actuated automatically upon and after the commencement of said forward stroke for causing said holder to grip said work piece.

4. The combination in a machine of the class described, of a movably mounted tool, means for moving said tool axially through forward and reverse strokes, means including an electric circuit for controlling said forward and reverse strokes, a work holder adapted to receive and grip a work piece, means actuated by a work piece in said holder for actuating said circuit to initiate a forward stroke of said tool, and means comprising an electric circuit actuated upon the forward movement of said tool for causing said holder to grip said work piece.

5. The combination in a machine of the class described, of a movably mounted tool, means operated by compressed air at one pressure for retracting said tool and normally holding it in a retracted position, means including a part of said first-named means and actuated by compressed air at a higher pressure for moving said tool axially through a working stroke against said first-named air pressure, means including an electric circuit for controlling the action of said compressed air operated means, a switch connected in said circuit and adapted to be actuated at the will of the operator for controlling the admission of compressed air at said higher pressure to said compressed air operated means to start said forward stroke, and another switch connected in said circuit and adapted to be actuated by the initial forward movement of said tool for maintaining the admission of compressed air at said higher pressure to said compressed air operated means during the continuance of said forward stroke.

6. The combination in a machine of the class described, of a movably mounted tool, means operated by compressed air at one pressure for retracting said tool and normally holding it in a retracted position, means including a part of said first-named means and actuated by compressed air at a higher pressure for moving said tool axially through a working stroke against said first-named air pressure, means including an electric circuit for controlling the action of said compressed air operated means, a switch connected in said circuit and adapted to be actuated at the will of the operator for controlling the admission of compressed air at said higher pressure to said compressed air operated means to start said forward stroke, and another switch connected in said circuit and adapted to be actuated by the initial forward movement of said tool for maintaining the admission of compressed air at said higher pressure to said compressed air operated means during the continuance of said forward stroke.

sure to said compressed air operated means to start said forward stroke, another switch connected in said circuit and adapted to be actuated by the initial forward movement of said tool for maintaining the admission of compressed air at said higher pressure to said compressed air operated means during the continuance of said forward stroke, and a third switch connected in said circuit and adapted to be actuated after a predetermined forward movement of said tool for permitting said air at a higher pressure to be exhausted from said compressed air operated means and thereby allowing said tool to be retracted by the operation of said low pressure air.

7. The combination in a machine of the class described, of a movably mounted tool, means operated by compressed air at one pressure for retracting said tool and normally holding it in a retracted position, means including a part of said first-named means and actuated by compressed air at a higher pressure for moving said tool axially through a working stroke against said first-named air pressure, means including an electric circuit for controlling the action of said compressed air operated means, a switch connected in said circuit and adapted to be actuated at the will of the operator for controlling the admission of compressed air at said higher pressure to said compressed air operated means to start said forward stroke, another switch connected in said circuit and adapted to be actuated by the initial forward movement of said tool for maintaining the admission of compressed air at said higher pressure to said compressed air operated means during the continuance of said forward stroke, a third switch connected in said circuit and adapted to be actuated after a predetermined forward movement of said tool for permitting said air at a higher pressure to be exhausted from said compressed air operated means and thereby allowing said tool to be retracted by the operation of said low pressure air, and a safety switch connected in said circuit and adapted to be operated at the will of the operator to exhaust said higher pressure air from said compressed air operated means and to permit said tool to be retracted by said low pressure air.
